UNITED STATES PATENT OFFICE.

FAIRLEIGH S. DICKINSON, OF RUTHERFORD, NEW JERSEY.

CASE.

1,156,762.

Specification of Letters Patent. Patented Oct. 12, 1915.

Application filed October 27, 1914. Serial No. 868,813.

To all whom it may concern:

Be it known that I, FAIRLEIGH S. DICKINSON, a citizen of the United States, and a resident of Rutherford, in the county of Bergen and State of New Jersey, have invented a new and Improved Case, of which the following is a full, clear, and exact description.

The invention relates to metallic shipping and storing vessels, and its object is to provide a new and improved metallic case or box having a box body and a hinged cover, and more especially designed for holding hypodermic and other syringes and other articles and devices, and arranged to permit of cheaply manufacturing the case or box, to hold the cover against lateral shifting on the box body without the use of special reinforcements, and to provide a simple and efficient locking device for normally holding the cover in locked position on the box body.

In order to accomplish the desired result, use is made of a box body and a cover hinged thereon, the opposite edges at the front and ends of the box body and cover having interlocking lugs and recesses, of which the interlocking lugs and recesses at the front of the cover hold the cover against lengthwise movement on the body, and the interlocking end lugs and recesses serve to hold the cover against transverse movement on the box body and thus relieve the hinge of undue strain. Use is also made of a retainer or support for holding the article to be stored or contained in the case or box, the support being inserted in the box body and having means for removably holding the article in position, the retainer having an integral locking member in the form of a spring catch adapted to be engaged by a keeper on the cover, the spring catch having a finger piece projecting into a slot in a wall of the box body to permit the user to readily manipulate the locking member from the outside for unlocking the box.

A practical embodiment of the invention is represented in the accompanying drawings forming a part of this specification, in which similar characters of reference indicate corresponding parts in all the views.

Figure 1 is a perspective view of the case with the cover in open position; Fig. 2 is a front elevation of the same with the cover in closed position; Fig. 3 is an enlarged transverse section of the same on the line 3-3 of Fig. 2; Fig. 4 is a similar view of

the same on the line 4-4 of Fig. 2 and with the cover in open position; Fig. 5 is a side elevation of the holder or support for supporting the article to be carried in the case 60 or box; and Fig. 6 is an inverted plan view of the same:

The metallic case in its general construction consists of a box body A and a similarly shaped cover B, the rear walls A', B' of the said body and cover being connected with each other by a hinge C to permit of conveniently opening or closing the case or box. The front walls A², B² of the body A and cover B as well as the end walls A³, B³ 70 are provided with interlocking means to hold the cover B against lateral movement when in closed position. Thus for the purpose mentioned, the front wall A² of the body A is provided at its upper edge with an upwardly extending lug D at one side of the median line of the box body and with a recess D' at the other side of the said median line, as plainly indicated in Fig. 2, and the said lug D is adapted to engage a correspondingly shaped recess E formed in the front wall B² of the cover B, and the recess D' is adapted to be engaged by a correspondingly shaped lug E' formed in the front wall B² of the cover B. The end walls A³ of the box body A are provided at their upper edges with upwardly extending lugs D² into which fit correspondingly-shaped recesses E² formed in the lower edges of the end walls B³ of the cover B. It will be noticed that when the cover B is in closed position on the box body A, the lugs D and E' are in engagement with the recesses E and D' to hold the cover against longitudinal movement, and the lugs D² in engagement with the recesses E² to hold the cover against transverse movement on the box body A, and consequently the hinge C is relieved of all undue strain and no special reinforcing means are required for holding the cover B against lateral shifting on the box body A.

In the box body A is inserted a retainer, preferably in the form of a plate F provided with clips G or like retaining devices for holding syringes or other articles in place in the case or box. The plate F is provided at its rear edge with upwardly extending flanges H each provided with a struck-up lug H' adapted to fit into an indentation H² formed in the rear or back wall A' of the box body A. The upper end H³ of each flange H extends beyond the top of the box body

and is bent rearwardly to bear against the inner face of the rear wall B' of the cover B when the latter is in a closed position. It will be noticed that when the cover B is 5 swung into closed position the flanges H are placed under tension by the rear wall B' of the cover B, and when the front end of the cover is unlocked then the cover is started into an opening position by the action of 10 the flanges H.

At the front edge of the plate F, preferably at the middle thereof, extends upwardly a locking member in the form of a spring catch I' having an outwardly extending struck-up finger piece I' fitting into a slot J formed in the front wall A² of the box body A so that the user of the box can engage the finger piece I' from the outside to press the catch I rearwardly into an 15 unlocking position. The upper end of the spring catch I is provided with a struck-up lug I² adapted to engage a struck-up keeper K on the front wall B² of the cover B so that when the cover B is swung into closed 20 position the lug I² engages the keeper K thus holding the cover B in locked position 25 on the body A.

It will be noticed that by the arrangement described the plate F is held securely in 30 position in the box body A by the lugs H' engaging the indentations H² and the finger piece I' engaging the slot J so that endwise or upward movement of the plate is prevented, but when it is desired to remove the 35 plate from the box body it is only necessary for the operator to press the flanges H and the spring catch I inwardly toward each other to disengage the lugs H' from the indentations H² and the finger piece I' from 40 the slot J to allow of lifting the plate F out of the box body. It will also be noticed that by the arrangement described the plate F can be readily inserted in the box body and locked therein by the means described.

45 It is understood that when the cover B is swung into closed position the lug I² readily snaps into engagement with the keeper K to securely hold the cover B in locked position, and when the user presses the finger piece I' in the inward direction then the lug I² is disengaged from the keeper K and the spring flanges H now swing the cover B into partly open position to allow the operator to readily open the cover to full extent 50 with a view to obtain access to the desired articles held in the clips G.

In practice the several parts of the box are made of sheet metal and the parts can be readily shaped by stamping, and by the 60 construction described the parts can be readily assembled thus permitting of manufacturing the case or box at a comparatively low cost.

Having thus described my invention, I claim as new and desire to secure by Letters 65 Patent:

1. A case, comprising a body provided at the front with a slot, a cover hinged to the back of the body, and a supporting plate adapted to be inserted into the said body, 70 the said supporting plate being provided at the rear edge with an upwardly extending retaining flange, the latter and the back of the body having interlocking means, the upper end of the said flange projecting 75 above the body and being bent rearwardly to bear on the inner face of the back of the cover when the latter is in closed position, the said supporting plate being provided at the front with an upwardly extending integral spring catch having a finger piece 80 projecting into the said slot, the said spring catch and the front of the cover having interlocking means engaging one the other on closing the cover to lock the latter when in 85 closed position.

2. A case, comprising a body provided at the front with a slot, a cover hinged to the back of the body, and a supporting plate adapted to be inserted into the said body, 90 the said supporting plate being provided at the rear edge with an upwardly extending retaining and cover opening flange, the latter and the back of the body having interlocking means, the said supporting plate being provided at the front with an upwardly extending integral spring catch having an integral finger piece projecting into the said slot, the upper end of the said spring catch 95 extending above the top of the body and being provided with a lug, and the front of the said cover being provided with a keeper adapted to engage the said lug on closing the cover.

3. A case, comprising a body having an 105 opening in its front wall and an indentation in its rear wall, a cover hinged to the body, and having a keeper on the inner face of its front wall, and a plate in the body and having means for supporting an article, said 110 plate being provided at its front with a spring catch having a member projecting through the slot of the body and at its rear with a flange having an integral lug projecting into the indentation of the body, the 115 upper end of the flange extending above the top of the body and bent rearwardly to bear against the inner face of the rear wall of the cover.

In testimony whereof I have signed my 120 name to this specification in the presence of two subscribing witnesses.

FAIRLEIGH S. DICKINSON.
